UNITED STATES PATENT OFFICE

155,097

DESIGN FOR A SHOWER HEAD

John P. Magos, Wilmette, and Carl Bolling, Chicago, Ill., assignors to Crane Co., Chicago, Ill., a corporation of Illinois

Application January 14, 1948, Serial No. 143,738

Term of patent 14 years

(Cl. D91—3)

To all whom it may concern:

Be it known that we, John P. Magos and Carl Bolling, citizens of the United States, residing at Wilmette and Chicago, respectively, in the county of Cook and State of Illinois, have invented a new, original, and ornamental Design for a Shower Head, of which the following is a specification, reference being had to the accompanying drawing, forming part thereof.

Fig. 1 is a plan view of the shower head embodying our new design.

Fig. 2 is a side elevation of same.

Fig. 3 is a bottom view of same.

We claim:

The ornamental design for a shower head, substantially as shown.

JOHN P. MAGOS.
CARL BOLLING.
